D. A. GURNEY

TRAIL STOP

Filed May 19, 1922

Dayton C. Gurney
Inventor

UNITED STATES PATENT OFFICE.

DAYTON A. GURNEY, OF CARO, MICHIGAN.

TRAIL STOP.

Application filed May 19, 1922. Serial No. 562,239.

(FILED UNDER THE ACT OF MARCH 3, 1883, 22 STAT. L., 625.)

To all whom it may concern:

Be it known that I, DAYTON A. GURNEY, a citizen of the United States, and a resident of Caro, in the county of Tuscola and State 5 of Michigan, have invented an Improvement in Trail Stops, of which the following is a specification.

The invention described herein may be used by the Government, or any of its officers or employees in prosecution of work for 10 the Government, or by any other person in the United States, without payment to me of any royalty thereon.

The subject of this invention is a trail 15 stop intended for use on gun carriages.

The main object of the invention is the provision of a stop which will limit the opening between the trails in a split trail carriage, when in battery, and which will 20 permit of the trails being brought together when the carriage is limbered.

With these and other objects in view, my 25 invention resides in the novel arrangement and combination of parts and in the details of construction hereinafter described and claimed, it being understood that changes in the precise embodiment of the invention herein disclosed may be made within the scope of what is claimed without departing 30 from the spirit of the invention.

A practical embodiment of the invention is illustrated in the accompanying draw-

ing, wherein is shown a rear elevation of a gun carriage constructed in accordance with the invention.

35

Referring to the drawing by numerals of reference:

In carrying out my invention I provide 40 wheels 10 mounted on an axle 11, which axle carries a top carriage 12 having a center pin 13 on the head of which is secured a bearing ring 14. A pair of trails 15 are pivotally connected, as at 16, to the top carriage or axle, as the case may be, and each trail is provided on its inner face with an eye socket 45

17. Connected to a rigid part of the gun carriage, specifically the ring 14, and each eye socket 17 is a flexible connector, such as a cable 18, of suitable length to permit the trails to be swung apart to the desired degree. As will be readily understood, the 50 connectors 18 being flexible, the trails may be swung toward each other when the carriage is to be limbered.

50

I claim: 55
The combination with a gun carriage, including an axle, a top carriage mounted on the axle, a center pin carried by the top carriage, a bearing ring mounted on the pin, and a pivotally mounted pair of trails, of 60 a flexible connection between each trail and the bearing ring.

DAYTON A. GURNEY.
